(57) **CLAIM**

The ornamental design for a housing for dispensing magazines, as shown and described.

DESCRIPTION

FIG. 1 is a perspective view of a housing for dispensing magazines showing my new design;

FIG. 2 is a front elevational view thereof;

FIG. 3 is a top plan view thereof;

FIG. 4 is a side elevational view thereof, of which the opposing side is a mirror image; and,

FIG. 5 is a rear elevational view thereof.

The broken lines in the drawings represent environmental structure only and form no part of the claimed design.
